UNITED STATES PATENT OFFICE

CHARLES LIONEL MARCUS, OF NEW YORK, N. Y.

DESIGN FOR A COMBINED ASH AND CIGARETTE RECEPTACLE AND HOLDER OR SIMILAR ARTICLE

Application filed June 10, 1930. Serial No. 36,009. Term of patent 7 years.

To all whom it may concern:

Be it known that CHARLES LIONEL MARCUS, citizen of the United States, and resident of New York city, in the county of New York and State of New York, has invented a new, original, and ornamental Design for a Combined Ash and Cigarette Receptacle and Holder or Similar Article, of which the following is a specification, reference being had to the accompanying drawing, forming part

thereof, in which the figure is a perspective view of a combined ash and cigarette receptacle and holder embodying my new design.

I claim:

The ornamental design for a combined ash and cigarette receptacle and holder or similar article, substantially as shown.

Dated, June 9, 1930.

CHARLES LIONEL MARCUS.
